UNITED STATES PATENT OFFICE

152,803

DESIGN FOR A NECKTIE

Nickolas Keramaris, Detroit, Mich.

Application January 27, 1948, Serial No. 144,076

Term of patent 14 years

(Cl. D3—16)

To all whom it may concern:

Be it known that I, Nickolas Keramaris, a citizen of the United States, residing at Detroit, in the county of Wayne and State of Michigan, have invented a new, original, and ornamental Design for a Necktie, of which the following is a specification, reference being had to the accompanying drawing, forming part thereof.

I claim:

The ornamental design for a necktie, as shown.

NICKOLAS KERAMARIS.
